CLAIM

The ornamental design for a tooth cleaner, as shown and described.

DESCRIPTION

FIG. 1 is a front view of a tooth cleaner according to the invention;

FIG. 2 is a back view of the tooth cleaner according to the invention;

FIG. 3 is a left side view of the tooth cleaner according to the invention;

FIG. 4 is a right side view of the tooth cleaner according to the invention;

FIG. 5 is a top view of the tooth cleaner according to the invention;

FIG. 6 is a bottom view of the tooth cleaner according to the invention;

FIG. 7 is a front, left, bottom perspective view of the tooth cleaner according to the invention; and,

FIG. 8 is a back, right, bottom perspective view of the tooth cleaner according to the invention.
